No. 651,218.

Patented June 5, 1900.

C. J. VOLLMER.

VENTILATOR.

(Application filed June 24, 1899.)

(Model.)

UNITED STATES PATENT OFFICE.

CONRAD J. VOLLMER, OF LAFAYETTE, INDIANA.

VENTILATOR.

SPECIFICATION forming part of Letters Patent No. 651,218, dated June 5, 1900.

Application filed June 24, 1899. Serial No. 721,704. (Model.)

To all whom it may concern:

Be it known that I, CONRAD J. VOLLMER, of Lafayette, in the county of Tippecanoe and State of Indiana, have invented a new and 5 Improved Ventilator, of which the following is a full, clear, and exact description.

The object of the invention is to provide a new and improved ventilator or grate and cover for use on buildings and arranged to 10 permit of conveniently uncovering the fixed grate for the passage of air to or from the part to be ventilated or to allow of covering the grate to exclude air in winter-time or during rainy weather.

15 The invention consists of novel features and parts and combinations of the same, as will be fully described hereinafter and then pointed out in the claims.

A practical embodiment of my invention is 20 represented in the accompanying drawings, forming a part of this specification, in which similar characters of reference indicate corresponding parts in all the views.

Figure 1 is a front view of the improvement 25 as applied. Fig. 2 is an enlarged sectional plan view of the improvement. Fig. 3 is a transverse section of the same on the line 3-3 in Fig. 2. Fig. 4 is a side elevation of the grate, and Fig. 5 is a like view of the cover.

30 The improved ventilator is provided with a grate having a suitable frame A set in the wall of the building on which the ventilator is to be used, and said grate is provided with vertically-disposed slats B, extending from a 35 rail B', integral with the bottom A' of the frame A, the upper ends of the slats B terminating in a rail B², integral with the sides of the frame A and located a suitable distance below the top A² of said frame to form sufficient space between the rail B² and the top A² 40 for the cover C to slide in at the time it is desired to leave the ventilator open for admission and exit of air to or from the building. (See dotted lines in Fig. 3.)

45 The cover C for the grate is provided with a bottom rail C', from which extend upwardly the integral slats C², arranged to close the spaces between the slats B of the grate, as is plainly shown in Figs. 1 and 2, to prevent air 50 from passing either to the building or from the same by way of the ventilator. The upper ends of the slats C² terminate in a rail C³,

which supports at its rear face a head C⁴, adapted to abut against the inner side of the top A² to close the space between the said top 55 and the rail B². Thus when the cover C is in position, as shown in Figs. 1, 2, and 3, the slats C² completely close the spaces between adjacent slats B, especially as said slats C² are somewhat wider than the distance between 60 two adjacent slats B. (See Fig. 2.) The bottom rail C' of the cover C in addition reaches to the upper face of the bottom A' of the frame in front of the rail B', and the upper rail C³ of the cover extends in front of the rail B², 65 the head C⁴ closing the space between the rail B² and the top A², so that no air can pass through the grate in either direction.

On the front of the cover C, preferably at the middle thereof, near the bottom, is arranged a knob D, adapted to be taken hold of by the operator to swing the cover C upward, with the upper ends of the slats C² as a fulcrum, on the rail B² to allow of bringing the cover into an approximately-horizontal 70 position to permit the operator to then push the cover C rearward to the position shown in dotted lines in Fig. 3. In order to hold the cover in this position, I provide the end slats C² of the cover with lugs E, located near the 75 bottom rail C', the said lugs abutting against the front of the top A² of the frame A to hold the cover C supported in an approximately-horizontal position, the main portion of the body being inside of the building. 85

If desired, the cover C can be entirely removed from the grate, and for this purpose the under side of the top A² of the frame A is provided with transverse notches A³ A⁴ for allowing the passage of the knob D and the 90 lugs E when the cover C is lifted from the position shown in dotted lines in Fig. 3 a sufficient distance and is then slid inward within the space between the rail B² and the top A² for the complete disengagement of the cover 95 from the grate. Normally, however, it is not necessary to remove the cover completely from the grate; but it can be left suspended in a raised horizontal position in the upper portion of the grate, as above described and 100 as shown in dotted lines in Fig. 3. It is understood that when the cover is in this position air can freely pass through the spaces between the slats B of the grate to or from

the building. When it is desired to again close the grate or cover the same by the cover C for the purpose mentioned, the operator simply pulls the cover C outward, and then 5 allows it to swing downward into the position shown in full lines in Figs. 1, 2, and 3, so that the slats C² again close the spaces between the slats B of the grate.

Having thus fully described my invention, 10 I claim as new and desire to secure by Letters Patent—

1. A ventilator, comprising a fixed grate having spaced slats and a space above said slats, and a cover having a swinging connection with the grate and slidable through the 15 space above said slats, as set forth.

2. A ventilator, comprising a grate having spaced slats extending from one side thereof, and terminating in a rail spaced from the opposite 20 side of the grate, and a cover slidable through the space between the rail and the adjacent side of the grate and having one end arranged to swing on said rail, as set forth.

3. A ventilator, comprising a grate having 25 a rail near one side and spaced from such side, and a cover for said grate, said cover being fitted to slide in the space between the rail and adjacent side of the grate and having one end arranged to swing on said rail, as set forth.

30 4. A ventilator, provided with a grate hav-

ing a frame, slats terminating at their upper ends below the top of the frame to form a space between the frame top and the upper ends of the slats, and a cover for said grate and provided with slats for covering the spaces between the slats of the grate, the cover being free to be moved transversely through the space formed between the frame top and the upper ends of the grate-slats, as set forth. 35

5. A ventilator, provided with a grate having a frame, slats terminating at their upper ends below the top of the frame to form a space between the frame top and the upper ends of the slats, a cover for said grate and provided with slats for covering the spaces 40 between the slats of the grate, the cover being free to be moved transversely through the space formed between the frame top and the upper ends of the grate-slats, and lugs on said cover for abutting against the top of the 45 frame, to hold the cover in an approximately horizontal position, the cover resting on the connecting-rail for the upper ends of the grate-slats, said cover abutting against the under side of the frame top, substantially as shown 50 and described.

CONRAD J. VOLLMER.
